UNITED STATES PATENT OFFICE.

ALEXANDER T. KASLEY, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE BLADING.

Application filed July 5, 1922. Serial No. 572,901.

To all whom it may concern:

Be it known that I, ALEXANDER T. KASLEY, a citizen of the United States, and a resident of Essington, in the county of 5 Delaware and State of Pennsylvania, have invented a new and useful Improvement in Turbine Blading, of which the following is a specification.

My invention relates to turbine blading, 10 more particularly to blading of the wide type adapted to receive steam at one side and to discharge it at the tips, and it has for its object to provide apparatus of the character designated which shall be rigid 15 in construction, simple in design, and inexpensive to build.

Apparatus embodying features of my invention is illustrated in the accompanying drawings, forming a part of this application, 20 in which: Fig. 1 is a sectional view of a turbine showing my improved type of blading applied thereto; and Fig. 2 is a fragmentary elevational view as observed from the right side of the wide blades in 25 Fig. 1.

In my co-pending application, Serial No. 521,872, filed December 12, 1921 and assigned to Westinghouse Electric and Manufacturing Company, there is disclosed blading of the wide type adapted to receive steam at one side and to discharge it at the tips. The wide blades disclosed in this application have inner substantially flat or radial portions and outer curved or spoon- 30 outline portions arranged to expand and to discharge steam at small peripheral angles. Curved ribs or deflector members are arranged between the blades in order to define deflecting walls to gradually change the 35 direction of steam from an axial toward a radial direction; and, as the rib or deflecting members are in contact, such rib or deflecting members constitute bracing means 40 for the blades.

As the tips of wide blading of the character referred to are arranged to discharge 45 directly to the exhaust chamber, there is a strong natural tendency for the steam passing between the blades to flow in stream lines under the influence of the highly 50 vacuous conditions fund in the exhaust chamber. This being so, the guide or deflector members need not extend entirely across the space between adjacent blades, 55 and it is, therefore, possible to cheapen the

construction for the reason that it is unnecessary to accurately fit the guide or deflector members to constitute curved deflecting walls, as set forth in my former application. Consequently, the cost of construction in this respect may be quite materially reduced. Of course, when the guide ribs or deflectors do not contact, the latter do not materially serve to brace the blading structure, and I have, therefore, provided lashing means at the inlet edges of the blades in order to brace the latter.

Referring now to the drawings for a more detailed description of my invention, I show a turbine having a rotor 10 and a casing or cylinder 11, with suitable energy-abtracting elements carried thereby including a last low-pressure stage, at 12, comprising a stationary row of guide blades 13 and a moving row of wide blades 14 made in accordance with my present invention.

The wide blades 14 are adapted to receive steam flowing in an axial direction from the row of guide blades or vanes 13 and to discharge the same peripherally or 80 at the tips. Each of the blades 14 comprises an inner approximately radial portion 15 and an outer curved or spoon-outline portion 16. Guide ribs 17 of any suitable type, for example, of the angle-section type, may 85 be formed on or secured to the blade portions 15 in any suitable manner for the purpose of assisting in changing the direction of flow of steam from an axial toward a radial direction. The guide ribs 17 extend 90 only part way across the spaces between the blades for the reason that the high vacuum condition obtaining in the exhaust chamber results in a strong natural tendency for the steam to flow in stream lines toward the 95 blade tips. I, therefore, provide guide ribs which merely assist this natural tendency.

As the guide ribs 17 do not extend across the spaces between the blades and do not contact, such guide ribs do not serve materially to brace the blading structure. It is, therefore, necessary to provide some means in order to brace or reinforce the blading structure to avoid vibration thereof. Accordingly, I have provided a plurality of lashing members 18 at the inlet edges 19 of the blades 14.

The inlet edges 19 are preferably inclined, as shown in Fig. 1, in order to provide extra strength to carry the lashing 110

members or wires. In other words, the inclination of the entering edges 19 of the blades presents increasing stress areas toward the blade roots in order to carry the 5 extra weight due to the lashing members.

From the foregoing, it will be apparent that I have devised blading of the wide type which has guide or deflecting members for changing the direction of steam which are 10 inexpensive to construct and which do not require accurate fitting. I have also devised suitable lashing means to be used with blading equipped with guide or deflector members of this character in order to limit 15 vibration of the blading structure.

While I have shown my invention in but one form, it will be obvious to those skilled in the art that it is not so limited, but is susceptible of various other changes and 20 modifications, without departing from the spirit thereof, and I desire, therefore, that only such limitations shall be placed thereupon as are imposed by the prior art or as are specifically set forth in the appended 25 claims.

What I claim is:

1. In a turbine, a row of blades having opposed guides on adjacent blade faces which extend part way across the space between the blades.
2. In a turbine, a row of blades having opposed guides less in width than half the distance between the blades.
3. In a turbine, the combination of a row of blades having opposed and spaced apart guide members on adjacent blade faces and lashing means cooperating with the blades to limit vibration thereof.
4. In a turbine, the combination of a row 40 of blades having opposed and spaced apart

guide members on adjacent blade faces and lashing means arranged at one side of the blades.

5. In a turbine, the combination of a row of blades adapted to receive steam at one side and to discharge it at the tips, opposed and spaced apart guide members on adjacent blade faces for assisting in changing the direction of flow of steam toward the tips of the blades, and lashing means cooperating with the inlet sides of the blades to limit the vibration thereof.

6. In a turbine, the combination of a row of exhaust blades adapted to receive steam at one side and to discharge it at the tips, opposed and spaced apart guide members on adjacent blade faces to assist in changing the direction of flow of steam between the blades toward the tips, and lashing means carried by the inlet edges of the blades, the inlet edges of the blades being inclined so as to provide sufficient supporting structure to withstand the centrifugal stresses due to the additional mass of the lashing members.

7. In a turbine, a row of trapezoidal blades having lashing means at the inclined side.

8. In a turbine, a row of trapezoidal blades adapted to receive steam at one side and to discharge it at the tips, and lashing means arranged at the inclined inlet side.

9. In a turbine, a row of trapezoidal blades, opposed and spaced apart guide members carried by adjacent faces of the blades, and lashing means arranged at the 75 inclined inlet side of the blades.

In testimony whereof, I have hereunto subscribed my name this 30th day of June, 1922.

ALEXANDER T. KASLEY.
